UNITED STATES PATENT OFFICE.

JOHN CRUM, OF RAMAPO, NEW YORK.

MACHINERY FOR CUTTING FILES.

Specification of Letters Patent No. 8,199, dated July 1, 1851.

To all whom it may concern:

Be it known that I, JOHN CRUM, of Ramapo, Rockland county, and State of New York, have invented certain new and useful Improvements in Machinery for Cutting Files, and that the following is a full, clear, and exact description of the same, reference being had to the accompanying drawings, making part of this specification, in which—

10 Figure 1, is a side elevation of the machine; Fig. 2, a front elevation; Fig. 3, a horizontal section taken at the line A, *a*, of Fig. 1; Fig. 4, a longitudinal vertical section taken at the line B, *b*, of Fig. 2; Fig. 5 cross 15 section of the carriage at C, *c*, Fig. 4; Fig. 6, cross section of the file bed at D, *d*, Fig. 4; and Fig. 7 vertical section of the feed motion.

The same letters indicate like parts in all 20 the figures.

Many machines have been invented and essayed for cutting files, but so far as I am informed none prior to my present invention have been practically useful, for the following 25 reasons. Files are usually made of a form presenting four faces which are more or less curved, slightly swelling from the handle toward the middle, and decreasing in a more sudden curve toward the point. These curves as the file passes under the cutter necessarily vary the range of the cutter's motion in cutting, the motion being greatest where the file is the thinnest and narrowest, so that the force of the blow is greatest where it should be the least. It follows from this state of things that the teeth will be cut deeper toward the point than at or toward the middle. Again the two 30 ranges of teeth cross each other at given angles to the axis of the file, and the motion of the cutter must be diagonal to the general plane of the face of the file to make the teeth pointing toward the top or point of the file. These peculiarities in the form of the body and teeth present serious practical 35 difficulties. If the cutting edge be made, as it should, at right angles to the plane of its motion to cut one range of teeth, when reversed by reason of its obliquity, the cutting edge will then be oblique to the face of the file, and only touch it at one edge, hence such an arrangement is impracticable. If the cutting edge be made diagonal to the plane 40 of its motion, and reversed for the second range of teeth, then the plane of motion of the cutter will be diagonal, and the force

of the blow will be greatest on one side in cutting one range of teeth, and greatest on the other in cutting another range, the result of which must necessarily be an imperfect file. And finally the curve of the face, and the diagonal range of the lines of teeth, slightly vary the relations of the cutting edges to the plane of the face to be cut as the file moves under the cutter from the 45 point to the handle, and from this it must follow that if the edge of the cutter or the face of the file are not made to shift as the file passes under the cutter, the cuts will vary, and the teeth produced be uneven.

All of the above practical difficulties I have avoided by my improvements which consists, first, in connecting the file blank to a bed which has a positive feed motion, and an incidental rolling motion depending 50 upon the shape of the blank and the angle which the cutter forms therewith; second, in connecting the cutter or chisel or the stock thereof with the slide, by which the power for cutting the teeth is applied by means of a joint the axes of which shall be at right angles or nearly so, with the face of the cutter, when this is combined with a rolling bed on which the blank rests, whereby the cutting edge and face of the blank become 55 mutually self adapting to the varying angles one to the curved face of the file, and the diagonal lines of the teeth; and, third, in holding down the file onto its bed or carriage as it progresses under the cutter, by means 60 of a roller which bears thereon just in front of the cutter whereby that part of the file which is being cut is held firmly down on to the bed notwithstanding the curvature of the faces, the said roller being made tapering 65 from the middle toward its ends, so as to be self adapting to any change of position of the face of the file, and the end of the file being held or connected with the bed or carriage by a clamp or the equivalent thereof, 70 which will permit that end of the file to rise and fall as the file is tilted on its bed by the pressure of the roller.

In the accompanying drawings *a*, represents the bed frame of the machine to which is properly secured the upper frame work *b*. The top of the bed frame is formed with two ways *c*, *c*, on which runs a carriage *d*, provided at one end with a block *e* that slides vertically in a recess. This block has a semi-circular groove, which is threaded to fit the threads of a feed screw *f* hung in journals

between the two ways *c*, *c*. And on the outer end the shaft of the screw is provided with a ratchet wheel *g* which is operated by a hand or pawl *h* connected by means of a wrist *i* that can be adjusted in the slot of an arm *j* on a rock shaft *k* the said rock shaft having another arm *l* to which is jointed the lower end of a vertical rod *m* that slides in a tube *n* surrounded by a helical spring *o*. The said spring rests at its lower end on a collar, and its upper end bears against a pin *p* that projects from the rod *m* and which slides in slots in the tube, so that the tension of the said spring shall always tend to force up the rod and thus draw back the hand or pawl *h* which at every revolution of the main shaft *q* is pushed forward to turn the ratchet the required distance by the connection of the hand with the arm of the rock shaft, acted upon by a cam *r*, on the main shaft which acts on the upper end of the rod *m*, properly formed for that purpose. In this way at each rotation of the main shaft, the carriage is moved forward the distance required for the cutting of one tooth. At the end of the feeding motion the carriage is moved back by the attendant who for this purpose must first disengage the block *e*, which is secured by a screw passing through a slot to the middle of a short lever *r'* connected with a hand lever *r''* which runs to the front end of the carriage to be within reach of the attendant.

The cutter or chisel *x* is formed with a stem, fitted and secured by a temper screw *y*, in the socket of the lower half of a stock *z*, which is jointed to the upper half by a screw bolt *a'*. The two halves of this stock are put together in the manner of the well known rule joint, so that the chisel or cutter shall have sufficient lateral play to adapt itself to the varying plane of the surface of the file. The upper end of the stock is fitted by a stem in a socket at the lower end of a heavy block of metal *b'*, called a slide, and there secured by a temper screw *c'*. The slide *b'*, is a quadrangular prism of the requisite weight which slides in two cross bars *d'*, *d'*, of the frame, each made in two parts connected together by screw bolts *e'* *e'* that they may be adjusted to the slide. The position of the slide is in a plane perpendicular to the transverse plane of the carriage which carries the blank and inclined back from a line perpendicular to the longitudinal plane of said carriage, so as to give the inclined cut required to make the teeth of the file sharp toward the point of the file. At about the middle of its length the slide is provided with a strap *f'* properly secured to it, which strap has two trunnions *g'* *g'* on opposite sides which play in the slots of two arms *h'*, *h'*, of a rock shaft *i'*, which has its bearings in the upper frame *b*, and which is provided with another arm *j'*, which at its

outer end carries a roller *k'* that is forced down to lift the slide and its cutter or chisel by means of a cam *l'*, on the main shaft *q*.

The cam *l'*, which operates the slide, has a greater sweep than, and begins to lift the cutter before the cam *r* begins to operate the feed motion, but so soon as the feed motion is completed the cam *l'*, liberates the rock shaft to permit the slide and chisel to descend and cut a tooth. As the rock shaft is operated to lift the slide a projecting piece *m'*, is brought in contact with a spring *n'* attached to a rock shaft *o'*, from which projects an arm *p'*, provided with a set screw *q'*, the point of which comes in contact with and is arrested by an arm *s'*, of a rock shaft *t'*, which has another arm *u'* that carries a roller *v'*, that runs on a plane *w'* attached to and carried by the carriage *d*. After the arm *p'*, of the rock shaft *o'*, has been arrested, the continued upward motion of the slides gives tension to the spring, the recoil of which aids in forcing down the slide to make the cut; hence the point at which the rock shaft *o*, is arrested will determine the force with which the blow will be struck. The general force of blows for the various kinds of files is regulated by the set screws *q'*, but the variation of this force for any one file is regulated by the plane *w'* on which the roller *v'* runs; the lower the plane the less tension the spring will receive and hence the less will be the force of the blow and vice versa. In this way the form of the plane *w'* can be modified to suit the form of file to be cut, that the force of the blow for cutting the teeth may be proportioned to the varying breadth of the file, and also to the varying distance of the surface of the file from the highest point of elevation of the cutting edge.

The line of the cutting edge of the cutter or chisel is diagonal to the line of motion of the carriage to correspond with the lines of one range of teeth, and, when shifted and reversed, corresponding with the lines of the second range of teeth.

The upper surface of the carriage is formed with a semi-cylindrical cavity *s*, to which is fitted the under surface of the bed *t*, so that it can roll therein; the form of the upper face of the said bed being adapted to receive the file blank to be cut. The one end of the bed is formed with a journal *u*, properly fitted to the end of the cavity in the carriage, and the journal is provided with a shoulder *v*, on the end to prevent the bed from moving endwise in the carriage, and the other end of the bed is provided with poppet heads or standards *w*, between which slide the journals of a clamp block *w''*, to which is secured the stem of the blank or file to be cut, so that the said clamp will be free to move therein. A brass roller *x'*, tapered from the middle toward the ends

is fitted to turn on the end of a spring arm y' and is so situated as to make pressure on the face of the file blank in front of the cutter or chisel, so as to hold it down steadily. 5 Either the journal on which this roller turns should be largest in the middle, or the hole in the roller should be enlarged from the middle toward each end, so as to avoid as much as possible all obstruction to the motion of the bed when the lateral inclination of the bed is shifted from the one side to the other.

When cutting the first range of teeth, the cutter and the bed, are in the position represented in the drawings and after the carriage has been run back, the cutter is shifted around so as to make its cutting edge cross the line of the first range of teeth, and as this varies the line of the cutting edge relatively to the face of the file blank, the bed must be turned to shift the inclination of the face of the file blank. But as the bed is free to roll, the first action of the cutter will effect the shifting of the bed if the attendant 20 should neglect to do it.

From the foregoing it will be seen that the cutter for cutting both ranges of teeth has its cutting edge at right angles to its line of motion and will at each cut strike 25 equally across the whole breadth of the file, with equal force. And that the force of the blow can be regulated by varying the form of the curved guide plane so as to adapt the force of the blow relatively to the form of the file, so that the force shall correspond 30 with the resistance; and finally by reason of the jointed connection of the cutter stock with the slide which operates it the edge, of the cutter will be rendered self adapting 35 to any slight variation in the surface of the file blank.

It will be seen from the foregoing that the file blank during the operation of the machine rests on and moves under the cutter 40 with the rolling bed which is longitudinally connected with and operated by the carriage and adapted to roll therein transversely to adapt the plane of the file to the line of the cutter edge. And as the clamp to which is 45 secured the stem of the file blank is free to move up and down in its connections with the bed, the roller which makes pressure on the face of the blank just in front of the cutter, will always keep it firmly onto the bed at that part of its length on which the cutter may be acting and this too without reference to the degree of curvature of the face of the file blank.

What I claim as my invention and desire 50 to secure by Letters Patent is—

1. Connecting the file blank to be cut with a bed which has a positive feed motion, substantially as described in combination with an incidental rolling motion depending upon 55 the shape of the blank and the angle which

the cutter forms therewith, substantially as described.

2. I also claim connecting the chisel with its stock by a joint as described in combination with a rolling bed as described, by 70 which they are rendered self adapting as described.

3. I also claim holding the file down on to the bed during the operation of cutting, and near to the cutter by means of a roller or 75 its equivalent combined with the rolling bed substantially as herein described, but this I only claim when the end of the file is so connected with its bed that it shall be free to move up and down that the pressure of the roller may keep that part of the file that is being cut, firmly down onto the bed, as herein specified.

4. I am aware that before the date of my invention, the cutter of filed cutting machines has been jointed to a valve or bar, but in such cases it has not been combined with a rolling bed and therefore I do not wish to be understood as claiming broadly the making of the cutter with a joint; but to 85 claim this only under the limitations pointed out above.

5. I am also aware that the file blank has been made to slide during the feeding motion over a rolling bed to adapt the transverse plane of the file blank to the line of the cutting edge for cutting the different ranges of teeth, and therefore I do not wish to be understood as claiming broadly the 90 employment of a rolling bed; but to claim such rolling bed when made to move with the file during the feed motion from end to end, under the limitations above specified.

JOHN CRUM.

To the Hon. Commissioner of Patents:

The petition of JOHN CRUM, of Ramapo, in the State of New York, and WILLIAM T. NICHOLSON, of the city and county of Providence, in the State of Rhode Island, respectfully represent that Letters Patent of the United States were on the 1st day of July, 1857, granted to the said CRUM for improvements in machinery for cutting files, 115 which Letters Patent by grant duly recorded in the Patent Office have been assigned to the said Nicholson; and your petitioners represent that they have reason to apprehend that through inadvertence and mistake 120 the claim to the connection of the chisel with its stock by a joint in combination with a rolling bed is too broad, including that of which the patentee has not a right 125 to claim.
